UNITED STATES PATENT OFFICE.

GEORGE R. RICH, OF OAK PARK, ILLINOIS, ASSIGNOR TO RICH TOOL COMPANY, OF CHICAGO, ILLINOIS, A CORPORATION OF ILLINOIS.

FLUE-EXPANDER.

1,048,584.

Specification of Letters Patent. Patented Dec. 31, 1912.

Application filed October 16, 1911. Serial No. 654,877.

To all whom it may concern:

Be it known that I, GEORGE R. RICH, a citizen of the United States, residing at Oak Park, in the county of Cook and State of Illinois, have invented new and useful Improvements in Flue-Expanders, of which the following is a specification.

This invention relates to flue expanders of that class employing an expanding member comprising a plurality of sector-like sections grouped together to form a cylindrical body arranged around a solid tapered core or mandrel.

One object of this invention is to avoid certain objectionable features heretofore present in flue expanders of this class. In using the ordinary flue expanders, much difficulty is encountered in maintaining the sector-like sections of the expanding member in alinement with the core or mandrel, the result being that when one of said sections gets out of alinement, it is usually broken in the course of work. Sometimes conical mandrels are employed in connection with a sectional expanding member, whose inner bearing surface is fitted to the mandrel at its smallest end, but it is obvious that when the larger end of the mandrel enters said expanding member in the work of expanding a flue, the corners of the inner bearing surfaces of the sections are in constant danger of being broken, because of the difference in radius of the bearing surfaces. I have overcome these objectionable features in the present flue expander which forms the subject matter of the present application.

The invention is clearly illustrated in the drawing furnished herewith in which—

Figure 1 is a side elevation of one form of my present invention, the expanding member occupying a position at the small end of the mandrel, Fig. 2 is an end view thereof looking in the direction of the arrow 2, in Fig. 1, Fig. 3 is a view of the flue expander with the expanding member moved to a position near the middle of the mandrel, the view being partly in side elevation and partly in longitudinal section, the line of section being indicated at 3—3 in Fig. 4, Fig. 4 is a view partly in end elevation and partly in cross section, the line of section being indicated at 4—4 Fig. 3, Fig. 5 is an end view of the mandrel looking in the direction of the arrow 2 in Fig. 1, and

Fig. 6 is a perspective view of one of the 55 sector-like sections.

Referring to said drawings A, represents a core or mandrel and B, an expanding member slidably mounted upon said mandrel and capable of being expanded radially thereof by the action of the mandrel thereon. Said member comprises a plurality of sector-like sections 10, freely grouped around its center as shown in Fig. 2, the exterior surface of said expanding member being shaped in conformity with the common practice to suit the work to be done. It is usual to taper one end slightly, as shown, and to provide an annular recessed portion 11, in the face of the expanding member. A central tapered opening 12, in the expanding member receives the tapered core or mandrel, which is forced therethrough in the operation of expanding a flue.

The mandrel and expanding member are 75 provided with co-acting bearing surfaces constructed and arranged to maintain the several sections of the expanding member in perfect alinement with the mandrel at any working position thereon and the form 80 illustrated in the drawing will now be described.

The mandrel A, is of tapered formation and has a number of longitudinal grooves 13, formed in its face, said grooves extending from its smaller end to a point near its larger end and being symmetrically disposed around the mandrel; the grooves corresponding in number to the number of sections comprising the expanding member. 85 In the form of the invention shown in the drawing, each groove is of curved formation, the radius of the arc of the curve being constant throughout the length of the groove, so that while the arc is of less extent 95 at the smaller end of the mandrel than at the larger end, the same curve is preserved throughout. Each section 10, of the expanding member B, is formed on its inner side with an outwardly curved bearing face 100 14, the arc of which has a radius equal to the radius of any of the grooves 13; said bearing face consequently fitting and conforming to any groove in said mandrel at any point in its length. The result is that 105 when the mandrel is forced through the central opening 12, of the expanding member, each section of said member is maintained

in perfect alinement with the mandrel and inasmuch as there is no change of the arc of the curve at any point in the groove, there is no danger of chipping or breaking off of the corners of the sections 10, or the ridges between the grooves of the mandrel. By reason of the peculiar formation of the grooves in the mandrel and the inner bearing faces of the freely grouped sector like 10 sections, said sections may rock on the mandrel to accommodate changes in the transverse section of the flue. In Fig. 3 one section 10^a, is shown in longitudinal section, for the purpose of illustrating the correct 15 alined position of any section of the expanding member at any point in the groove.

To hold the sections of the expanding member together, while permitting them to be moved outwardly radially, by the action 20 of the mandrel, I have provided yielding retaining members, here shown as comprising two split, spring rings 15, 16, that are seated in undercut portions of grooves 17, formed in the end faces of the expanding 25 member. Said rings, by reason of their elasticity, act to hold the several sections together upon the mandrel, and do not interfere with the handling of the expanding member because they are wholly confined 30 within the grooves.

In operation, the expanding member is inserted in the end of the flue and the mandrel driven through the central opening thereof, thereby forcing the sections of the 35 expanding member outward radially against the flue, and forcing the flue into contact

with the flue sheet. The several sections of the expanding member remain in perfect alinement with the mandrel by reason of the co-acting bearing surfaces between the sections and mandrel, hence enabling the tool to effect a more perfect expansion of the flue. 40

I realize that various alterations and modifications of this device are possible without departing from the spirit of my invention, and I do not therefore desire to limit myself to the exact form of construction shown and described. 45

I claim as new and desire to secure by Letters Patent:

A flue expander, comprising a tapered solid mandrel whose entire working face is formed with longitudinal grooves paralleling its face, each groove being curved in cross section and the radius of the curve 55 being constant throughout the length of the groove, and a substantially cylindrical expanding member comprising sector-like sections freely grouped around the mandrel, each section having an inner, outwardly 60 curved bearing face of the same radius as any groove on the mandrel, whereby said sections may rock thereon to accommodate changes in the transverse section of the flue. 65

In witness whereof I have hereunto signed my name at Chicago, Cook county, Illinois, this 12th day of October 1911.

GEORGE R. RICH.
